DESIGN FOR A FACE TISSUE BOX

Solomon Herz, New York, N. Y., assignor to Federated Mills, Inc., New York, N. Y., a corporation of New York

Application September 15, 1936, Serial No. 64,858

Term of patent 3½ years

To all whom it may concern:

Be it known that I, Solomon Herz, a citizen of the United States of America and residing in New York city, New York, have invented a new, original, and ornamental Design for a Face Tissue Box, of which the following is a specification, reference being had to the accompanying drawing, forming part thereof.

I claim:—

The ornamental design for a face tissue box, as shown.

SOL. HERZ.
